UNITED STATES PATENT OFFICE.

CHARLES J. KLEIN, OF MILWAUKEE, WISCONSIN.

LAMP.

1,262,517.

Specification of Letters Patent.

Patented Apr. 9, 1918.

Application filed May 31, 1913. Serial No. 770,968.

To all whom it may concern:

Be it known that I, CHARLES J. KLEIN, a citizen of the United States, residing at Milwaukee, in the county of Milwaukee and 5 State of Wisconsin, have invented new and useful Improvements in Lamps, of which the following is a full, clear, concise, and exact description, reference being had to the accompanying drawing, forming a part 10 of this specification.

This invention relates to improvements in lamps.

One of the objects of the invention is to provide a reflector for a vehicle lamp which 15 is shaped so that it will project a substantially oval beam of light.

Another object is to provide a one piece lamp body and reflector made out of material which can be molded into shape and 20 glazed on the outside for finishing the same and on the inside for providing a reflecting surface.

Another object is to provide a vehicle lamp in which the lamp body and reflector 25 are formed in one piece out of suitable plastic material.

A further object is to provide a reflector which will project an efficient beam of light having a minimum glaring effect.

30 A further object is to provide a lamp body and reflector which can be easily and inexpensively manufactured.

Another object is to provide a lamp body and reflector having a dark reflecting surface 35 for reducing the glare of the light.

Another object is to provide an improved means for adjusting the position of the light-giving element of a lamp with relation to the focus of the reflector.

40 A further object is to provide improved means for attaching the lamp to a support.

Another object is to provide improved means for securing the glass front of the lamp in place.

45 Other objects and advantages of the invention will hereinafter appear.

Figure 1 is a side elevation, partly in section, of the preferred form of my invention.

50 Fig. 2 is a vertical section on the line A—B of Fig. 1.

Fig. 3 is a view of a portion of the glass retaining ring shown in Fig. 1.

55 Fig. 4 is a side view, partly in section, of a modified form of lamp.

Fig. 5 is a front view of the lamp shown in Fig. 4.

Fig. 6 is a view of a portion of the glass retaining ring shown in Figs. 4 and 5.

Fig. 7 is an end view of the adjustable lamp sleeve.

Figs. 8 and 9 are diagrammatic views showing the parabolic outline of the reflector at sections taken on lines C—D and 65 E—F respectively of Fig. 5.

The body and reflector of the lamp illustrated in Fig. 1 comprises a bell-shaped structure 10, preferably molded in one piece out of plastic vitreous material and subsequently hardened or baked by any satisfactory process. Porcelain or pottery clay or other opaque vitreous material is suitable for this purpose. The exterior of the body may be ornamentally glazed in any desired color to give it a finished appearance and to provide a wearing surface which may be easily cleaned. The interior of the body is fire glazed with silver or other suitable material to provide a dark reflecting surface 10^a. The shape of the interior reflecting surface is, in general paraboloidal. In vertical and horizontal section the outline of the reflecting surface is a true parabola but the diameter of the parabolic outline at the vertical section is less than the diameter of the parabolic outline of the horizontal section, as will be hereinafter described.

Extending around the inside of the lamp, adjacent the front end thereof, is a shoulder 90 11 against which the glass front 12 is held by a split ring 13 that fits snugly into the circumferential groove 14, just forward of the shoulder 11. The split ring 13 is punched so as to provide a plurality of resilient fingers 15 which serve to hold the glass front 12 in place. Another form of split ring which may be employed to retain the glass front in position, is shown in Figs. 4, 5 and 6. As illustrated, the split wire ring 16 is provided with a plurality of sleeves 17, formed with resilient fingers 18 which press the glass front tightly against the shoulder 11.

As more clearly shown in Fig. 4, a sleeve 19 is fitted in the outwardly tapering opening 20 extending through the reduced end of the lamp. This sleeve serves as a holder for the socket 21, which in turn carries the bulb 22, and is secured in place by a plurality of resilient teeth 23 adapted to exert 105 110

pressure against the sides of said opening. It is obvious that the sleeve 19 may serve as a holder for a great variety of light-giving elements, and also that the opening 20 5 may be modified in contour to suit any desired form of sleeve. The teeth 23, which are shown more clearly in Fig. 7, are formed by cutting longitudinal slits 24 in one end of the sleeve and bending outwardly the 10 free edges provided thereby. That end of the sleeve which protrudes from the opening 20, is provided with screw-threads 25. A cup-shaped nut 26 turns on the threads 25, and is provided with an opening 27, through 15 which the electric leads 28 may be passed to the socket 21. This nut bears against the reduced end of the lamp and serves to regulate the position of the bulb 22 with relation to the focus of the reflector.

20 Girdling the reduced end of the lamp shown in Fig. 1, is a split band 29, the ends of which are formed with outwardly extending flanges 30. A bolt 31 passes through the openings 32 in said flanges, and is held 25 in place by a nut 33. By tightening said nut, the band may be contracted so that it will grip the lamp with great pressure. As an additional means for preventing the lamp from slipping or working loose, a plurality 30 of lugs 34 are formed on the inside of the band. These lugs fit snugly into the recesses 35 on the outside of the lamp. Attached to the band 29 is an eye 36, by which the lamp may be secured to any suitable 35 support. After the lamp has been placed on its support, it may be firmly clamped thereto by a set screw 37, fitted in an opening 38 in the wall of the eye 36.

The lamp shown in Figs. 4 and 5 is adapted to be supported from its front end. In this construction, the front end is formed with a broad, flat rim 39, and a built-out flattened base 40. The strap 41, which serves to secure the lamp in place, passes around 45 said rim and is fastened to any suitable support by its threaded extremities 42 and the nuts 43. In order to prevent the lamp from joggling loose, a plurality of lugs 44 are provided on the inside of the strap. These 50 lugs fit snugly into recesses 45 formed on the outside of the rim 39.

The reflectors heretofore used for vehicle lamps have been adapted to throw a circular beam of light, and consequently a great deal 55 of the light projected was dissipated upwardly into the air, instead of being concentrated on the road. It has been found that when a circular paraboloidal reflector is distorted so that one diameter is shorter 60 than the other that the beam of light projected thereby is widened, the major axis of the beam being at right angles to the minor axis of the reflector. I have made use of this phenomenon in the reflector herein

shown by forming the same in the shape of 65 a distorted paraboloid so that the reflected beam of light is widened. By placing the lamp in proper position the light may be projected so that the major axis of the beam is substantially horizontal and accordingly 70 when the lamp is used on a vehicle the light is efficiently distributed over the roadway. Fig. 8 shows the contour of the reflector on the line C—D, Fig. 5, and illustrates the 75 angles of incidence and reflection of the rays *a*, *a*, *a*, while Fig. 9 shows the contour of the reflector on the line E—F, Fig. 5, and illustrates the angles of incidence and reflection of the rays *b*, *b*, *b*. It is to be understood that by varying the location of 80 the distortion, the major axis of the beam may be given any desired angle.

A strong objection to vehicle headlights now in common use is that the light is so reflected as to cause a glare in the eyes of 85 the driver of a vehicle moving in the opposite direction. By employing a dark reflecting surface instead of a bright one such as is ordinarily used, it is possible to project the light so that it will not cause a glare on 90 the eyes when viewed from any other point than its focus.

It will be seen that a vehicle lamp has been provided which may be readily and inexpensively manufactured out of a comparatively inexpensive material. In addition to reducing the original cost and the cost of replacement of structures of this kind, a lamp has been provided which is simple, 95 neat, capable of being readily cleaned and 100 which distributes the light at points where it is needed with the least possible glaring effect. By constructing the lamp body out of vitreous material the outside surface thereof can be given a finished appearance 105 and it is free from corrugations and joints and can therefore be easily cleaned. Moreover, the body is rigid and consequently the interior reflecting surface cannot be distorted. This reflecting surface is fire glazed 110 into the material, and it therefore cannot be easily scratched or otherwise damaged. The reflecting surface is dark glazed so that it causes a minimum glare. The lighting element is secured in the body through a 115 simple opening therein and it may be adjusted without necessitating the manipulation of complicated parts. This feature also enables the body to be simply constructed. A distorted paraboloidal reflecting surface, such as herein disclosed, throws 120 an oval beam of light which may be adjusted so that its major axis is horizontal thereby distributing a concentrated beam of light over the surface of the road.

125 It should be understood that the structure shown and described herein is for purposes of illustration only and that other structures

may be devised embodying the invention which are included within the spirit and scope of the appended claims.

It should also be understood that the expression distorted paraboloid does not mean that the vertical and horizontal parabolic outlines of the reflector are distorted into untrue parabolas. In other words, the horizontal and vertical outlines of the reflector may be true parabolas in spite of the fact that the paraboloid is distorted.

Having fully and clearly described my invention, what I claim as new and desire to secure by Letters Patent is:

15 1. A vehicle lamp having an integral body formed of molded vitreous material, said body being glazed on the outside to form a finished surface and being dark glazed on the interior to provide a non-glaring reflecting surface.

20 2. A vehicle lamp having an integral body formed of molded vitreous material, said body being glazed on the outside and formed with a distorted paraboloidal interior reflecting surface for projecting an oval beam of light.

25 3. A vehicle lamp having an integral body formed of molded vitreous material, said body being glazed on the outside and formed with a distorted paraboloidal dark glazed interior reflecting surface for projecting a non-glaring oval beam of light.

30 4. A vehicle lamp having an integral body formed of molded vitreous material, said body having a distorted paraboloidal inner surface dark glazed to project a non-glaring oval beam of light, said body having an opening therein and means in said opening for adjustably supporting a light-giving element in said body.

35 5. An automobile lamp having a body formed of opaque vitreous material glazed on the outer surface and provided with a glazed interior parabolic reflecting surface.

40 6. A lamp, comprising a molded body formed with a reduced end and having an interior reflecting surface, a retaining band extending around said reduced end, means attached to said band to prevent said body from slipping, and supporting means formed on said band.

45 7. A lamp, comprising a body having a reduced end, said reduced end being provided with a plurality of recesses, a strap 55 girdling said reduced end, a plurality of lugs formed on the inside of said strap and adapted to fit in said recesses, and means whereby said strap can be caused to firmly grip said reduced end.

80 8. A headlight, comprising a molded body having a distorted parabolic interior dark reflecting surface adapted to throw an oval

beam of light, a light-giving element carried within said body, and means for adjusting said light-giving element with relation to the focus of the reflector.

9. An adjustable sleeve for lamps, comprising a member having a plurality of longitudinal slits at one end and a screw-thread at the other, a plurality of resilient teeth on the outside of said member formed by bending outwardly the edges provided by said longitudinal slits, and a nut fitted on the threaded end of said member.

10. In combination with a lamp having an interior reflecting surface formed with a circumferential groove, a front for said lamp, a retaining ring fitting in said groove, and a plurality of sleeves carried by said ring, said sleeves being formed with outwardly extending resilient fingers for holding said front in place.

11. In combination with a lamp body having an interior reflecting surface formed with a circumferential groove, a glass front for said lamp, a retaining ring fitting in said groove, and a plurality of resilient fingers connected to said ring.

12. A lamp body provided with a distorted interior paraboloidal reflecting surface having the contour of a true parabola along the vertical and horizontal diameters.

13. A lamp body provided with an interior reflecting surface having the contour of a true parabola along the vertical and horizontal diameters and having the diameter of one parabola shorter than that of the other.

14. A lamp body provided with an interior reflecting surface having the contour of a true parabola along the vertical and horizontal diameters and having the diameter of the vertical parabola shorter than that of the horizontal parabola.

15. A lamp comprising a body portion formed of molded vitreous material and having a parabolic reflecting surface and a source of light positioned near the focal point of the reflector.

16. A lamp comprising a body portion formed of a molded vitreous material having a glazed surface, said surface being shaped to form a parabolic reflector.

17. A vehicle lamp comprising a body portion formed of a molded vitreous material and having a distorted paraboloidal interior reflecting surface.

In witness whereof, I have hereunto subscribed my name in the presence of two witnesses.

CHARLES J. KLEIN.
